UNITED STATES PATENT OFFICE.

WILLIAM GALT CHIPLEY, OF ATLANTA, GEORGIA.

REINFORCED TIE.

1,088,062.

Specification of Letters Patent.

Patented Feb. 24, 1914.

Application filed May 24, 1913. Serial No. 769,705.

To all whom it may concern:

Be it known that I, WILLIAM G. CHIPLEY, citizen of the United States, residing at Atlanta, in the county of Fulton and State 5 of Georgia, have invented certain new and useful Improvements in Reinforced Ties; and I do hereby declare the following to be a full, clear, and exact description of the invention, such as will enable others skilled 10 in the art to which it appertains to make and use the same.

This invention relates to reinforced concrete ties.

One of the chief objects of the invention 15 is to provide a tie, the body portion of which shall be substantially rectangular in form and be uniform in size throughout its length, the said body portion having no recesses or the like therein for the reception of the rail, 20 such recesses being provided however in an upwardly projecting member formed upon and integral with the tie proper.

A further object is to provide a particular and improved type of reinforcement 25 which involves the use of a channel member preferably formed of expanded metal and having its central flat portion located adjacent the upper surface of the tie, the open portion of the channel and the free 30 edges thereof being adjacent the lower side of the tie.

A further object is to provide in connection with a reinforcement such as that mentioned, which is of uniform size throughout 35 the length of the tie, an additional reinforcement which in the preferred form of my device may consist of a plurality of heavy longitudinal wires or rods, and in another form of a wire mesh, the additional 40 reinforcement in either case being located between the channel member and upper surface of the tie and being deflected adjacent the walls of the recesses for receiving the rails in order to reinforce the said walls, and 45 to reinforce the lower wall of the recess and the body portion of the tie proper below the recess, the metallic structure extending to the base of the tie.

Particular emphasis is laid upon a stirrup 50 like member formed as shown in Fig. 7, which reinforces the edge portions of the walls of the recess and extends to the base of the tie, and further ties the body portion by means of that portion which lies adjacent to the edge of the walls, extending

from one side of the body portion to the other side.

In the accompanying drawings: Figure 1 is a view of the tie partly in side elevation and partly in vertical longitudinal section, 60 the central portion of the tie being broken away. Fig. 2 is a fragmentary view partly in top plan and partly in horizontal section showing the arrangement of the longitudinal wire reinforcement. Fig. 3 is a vertical transverse section through one of the recesses for receiving the rails. Fig. 4 is a view in vertical section of one end of a tie showing a slightly modified form of reinforcement. Fig. 5 is a top plan view of certain of the 70 structure shown in Fig. 4. Fig. 6 is a vertical transverse section of the modification taken through one of the recesses. Fig. 7 is a perspective view partly in section of a portion of a tie showing a recess and a particular type of reinforcement therefor also incorporated in the structure shown in Figs. 4 and 5. Fig. 8 is a detail showing the wire mesh illustrated in top plan in Fig. 5, before being folded as in Fig. 6.

In the several views the tie is indicated by 10 and the recesses for the reception of the rails by 15 and 16. The tie is substantially rectangular in cross section throughout its body portion and is reinforced by a 80 channel like device 17 which may be formed of expanded metal which is also of uniform size throughout its length. The open side of the channel is on the lower side of the tie so that the upper portion thereof and the 85 sides of the tie are fully reinforced by a member of arch like construction, the crown of the arch being at the top. Additional reinforcement is provided by employing heavy 90 wires or rods 18 which extend from the lower side of the tie at each end upwardly next to the surface of the end portion, and then extend lengthwise of the tie to the edge of the adjacent recess for the rail. The wires 18 and 18^a adjacent to the sides of the 95 tie extend outwardly in the direction of the inner tapered walls 19 of the recesses and further extend to a point near the base of the tie on the outer side of the channel reinforcement.

The formation of the outer wires is shown in Fig. 1 and it will be seen that a stirrup like member is provided which extends for a short distance along the base portion of the tie below the recess of the rail and re- 110

inforces the walls of the recess as well as the sides of the tie and a portion of the base. The outer wires further reinforce that portion of the body of concrete which is disposed above the tie proper at points 20 and 21 adjacent the recesses. The object of this additional reinforcement and additional thickness of the body portion at the point stated is to provide additional strength where the rails have their bearing. To state the matter differently, a reinforced tie constructed to withstand the maximum strain if provided with recesses directly in the body portion thereof has, or will have, under the present construction an additional margin of safety of a very material extent. The thickened portions 20 and 21 are further reinforced, as is also the tie throughout its length and within its upper surface by several intermediate wires or rods designated 18'. These wires have a stirrup like formation of less extent than that of wires 18 and 18^a, the lower portion of the stirrup being embedded in the lower wall of the recess. In the drawings I have shown a metallic chair or rail supporting device 25 which has its bearing on a wooden block 26 mounted directly above the lower wall of the recess. The block is provided in order that the rail may be suitably cushioned and the chair member is ordinarily tapered from end to end for the reception of wedge blocks correspondingly tapered as shown in my U. S. Patent No. 1,030,230, issued June 18, 1912. In the modification shown in Fig. 4 and the following views of the drawing, the body portion and the channel reinforcement are of similar construction. Instead of employing longitudinal tie rods separated from one another as in Figs. 1 and 2, I employ in the modification a wire mesh which may comprise a central portion 30 constituting one layer of the mesh when embedded in the tie and portions 31 and 32 which are folded beneath portion 30 in the manner shown in Fig. 6, in order to form a double thickness of the mesh when considered as a reinforcement in itself. This wire mesh structure is deflected as shown in Fig. 4, around the recesses of the tie, and reinforces the side and lower walls thereof, as described in connection with the preferred form. I do not carry any portion of this wire mesh to the base of the tie, but provide an additional reinforcement for the portion supporting the rails by employing a device which may be termed a double stirrup member 35 having lower portions 36 located near the base of the tie below the recess, upwardly extending and inwardly inclined portions 37 which project along side of the walls of the recesses, and the transverse members 38 which are located within the walls adjacent the extreme edges thereof and extend from one side of the tie to the other for the purpose of reinforcing

and tying together this portion of the concrete body. It will be observed that a reinforced pedestal is provided below the rail which in a measure constitutes a separate reinforced rail supporting device, and is largely independent of the reinforcement extending the full length of the tie. 70

Transverse strips 8 are perforated and arranged across the longitudinal wires, as in Figs. 1 and 2, for holding the wires apart until the concrete is poured and has properly set. As many of these transverse strips may be employed as desired. 75

What I claim is:—

1. In a tie, a body portion proper of concrete provided with upwardly extending portions integral with the body portion, said upwardly extending portions having transverse recesses therein for the reception of the rails, a reinforcing device arch shaped 80 in cross section below the recesses and stirrup-like members for reinforcing the walls of the recesses, said stirrup-like members being extended through the upper portion of the body of the tie. 85

2. In a tie, a body portion proper of plastic material substantially rectangular in cross section throughout its length, said body portion being provided with upwardly extending members forming a recessed rail receiving portion, and means for reinforcing said members on their upper sides and along the sides adjacent the recesses, a portion of the reinforcement extending immediately below the lower wall of the recesses and a portion extending to the base of the tie below the recesses, a reinforcing device arch shaped in cross section below the recesses. 95

3. In a tie, a body portion of concrete substantially rectangular in cross section 105 throughout its length, members formed integrally with the body portion and projecting upwardly therefrom for forming rail receiving recesses, said members being reinforced near their exposed surfaces and being tied to the tie proper at a point adjacent to its base portion and an inverted channel reinforcing member extending transversely of the rail and longitudinally of the tie. 110

4. In a tie, a body portion proper of concrete, a channel reinforcement therefor, such channel having a portion disposed near the upper surface of the tie and being of substantially continuous mesh, upwardly extending members oppositely located projecting from the tie and forming a recess for the reception of a rail, and reinforcing devices for said members, said devices being embedded in the body portion between the sides thereof and the sides of the channel 115 reinforcement. 120

5. In a tie, a body portion proper of plastic material substantially rectangular in cross section, upwardly projecting and oppositely located members integral with the body por- 130

- tion and forming a recess for the reception of a rail, a plate-like member located within the recess above the lower wall thereof, reinforcing devices extending below said plate 5 and projecting upwardly on each side thereof, thence in opposite directions near the upper surface of the projecting members, other reinforcing devices located near the upper edges of the tie below its upper surface and extending downwardly to the base of the tie below the recess and a channel reinforcing device, coöperating with the reinforcement extending to the base, in reinforcing the side walls of the tie.
- 10 6. In a tie, a body portion of plastic material having a cross section where the rails are designed to rest substantially equivalent to the cross section of the portion intermediate of the rails, members formed integrally with the tie for retaining rail securing devices, a reinforcing structure for said members and the tie proper and an arch shaped reinforcement having the crown of the arch within the base of said integrally formed members.
- 15 7. In a tie, a body portion of plastic material having a cross section below the rails substantially equivalent to the cross section of the portion of inverted U-formation intermediate of the rails, members formed integral with the tie for retaining rail securing devices and a reinforcing structure for said members and the tie proper, said structure comprising a plurality of elements extending substantially the full length of the tie, one of said elements being of approximately uniform cross section and approaching the cross section of the tie at its central portion.
- 20 8. In a tie, a body portion formed of plastic material having enlarged end portions provided with recesses for the reception of the rails, that portion of the tie beneath the rails having a cross section substantially equivalent to the remainder of the tie, a longitudinal reinforcing member of substantially uniform cross section and approaching the cross section above mentioned, and an independent stirrup like member reinforcing the walls of the recess and extending to the base of the tie beneath the rails, said longitudinal reinforcing member passing between portions of the stirrup like member.
- 25 9. In a tie, a body portion formed of plastic material having enlarged end portions provided with recesses for the reception of the rails, a stirrup like member reinforcing the walls of each recess and extending to the base of the rails, and a longitudinal reinforcing member disposed between portions of the stirrup member.
- 30 10. In a tie, a body portion formed of plastic material and having recesses for the rails, a stirrup like member reinforcing the walls of each recess and extending from one side of the tie to the opposite side, portions extending to the base of the tie, and a reinforcing member connected with the end portions of the tie and being disposed at a given point between spaced portions of the stirrup member.
- 35 In testimony whereof I affix my signature in presence of two witnesses.
- WILLIAM GALT CHIPLEY.
